UNITED STATES PATENT OFFICE.

JOHN LOUIS SABBATH, OF MONTREAL, QUEBEC, CANADA.

DESIGN FOR A BRACELET.

60,470.

Specification for Design.

Patented Feb. 21, 1922.

Application filed June 27, 1921. Serial No. 480,931. Term of patent 7 years.

To all whom it may concern:

Be it known that I, JOHN LOUIS SABBATH, a British subject, residing in the city of Montreal, in the Province of Quebec, in the Dominion of Canada, have invented a new, original, and ornamental Design for Bracelets, of which the following is a specification, reference being had to the accompanying drawing, forming part thereof.

In the accompanying drawing:

Figure 1 is a plan view showing the present design as applied to a bracelet.

Fig. 2 is an enlarged detail view showing the configuration of the smaller intermediate member.

The present invention relates more particularly to the disk-like intermediate member which has the appearance of a continuous coil. This appearance may be produced by forming the member with spiral grooves or by winding a comparatively fine wire thereon. However, so far as the present invention is concerned it may be produced in any other manner.

I claim:

The ornamental design for a bracelet as shown.

JOHN LOUIS SABBATH.
